UNITED STATES PATENT OFFICE.

JAMES ELBERT BIRDSALL, OF PHILADELPHIA, PENNSYLVANIA, ASSIGNOR, BY
MESNE ASSIGNMENTS, TO ADVERTISING DEVICE COMPANY, A CORPORATION
OF DELAWARE.

MECHANICAL-SHOE-POLISHING MACHINE.

1,136,647.

Specification of Letters Patent. Patented Apr. 20, 1915.

Application filed March 30, 1912. Serial No. 687,529.

To all whom it may concern:

Be it known that I, JAMES ELBERT BIRDSALL, a citizen of the United States, residing at No. 166 North Farson street, Philadelphia, in the county of Philadelphia and State of Pennsylvania, have invented a new and useful Mechanical-Shoe-Polishing Machine, of which the following is a specification.

10 My invention relates to improvements in shoe polishing machines automatically operated by power and which are started and stopped by electrical means and the operation of which may be controlled by the introduction of a coin, check, or otherwise, as may be desired.

15 The objects of my invention are, first: to provide a device which will operate only when the shoe is properly and correctly placed on the foot pedestal, and not otherwise; second: to provide a means for applying blacking to the shoe in paste form and not in liquid condition; and, third: to provide a method of brushing the shoe by 20 various motions of the several brushes, in a manner closely resembling the motions used when the operation is performed by hand, whereby the effective product is similar to a polish made by hand.

25 30 For the purpose of illustrating my invention, I have shown in the accompanying drawings one form thereof which is at present preferred by me, although it is to be understood that the various instrumentalities of which my invention consists can be variously arranged and organized and that 35 my invention is not limited to the precise arrangement and organization of these instrumentalities as herein shown and described.

40 I attain the objects stated by the mechanism illustrated in the accompanying drawings, in which—

45 Figure 1 is a side elevation of the machine with the outside casing removed and parts broken away to show posterior construction; Fig. 2, a plan view of the same; Fig. 3, an end elevation of the same viewed from left to right on Fig. 2; Figs. 4 and 5, detailed 50 views of the side brush mechanism; Fig. 6, a section view of the blacking apparatus; as normally, at rest; Fig. 7, a front elevation of the same; Fig. 8, a section view of the same

as compressed under the action of a brush acquiring blacking; Fig. 9, a detail view, 55 partly in section, of the cam mechanism operating the toe brush; Fig. 10, a detail view of the stopping mechanism; Fig. 11, a detail side elevation of the heel brush actuating mechanism, with foot rest in section; 60 Fig. 12, a plan view of same, with parts broken away to show underlying construction; and, Fig. 13, a detail of the controlling mechanism for the toe brush.

Similar letters refer to similar parts 65 throughout the several views.

I make no claim as to the method of controlling the starting and stopping of the electric current whereby the same is initially introduced and maintained. Any of the 70 well known automatic coin controlled devices may be applied for this purpose. My invention concerns means for automatically polishing boots and shoes.

The form and design of the outside cabinet or casing is immaterial and may be varied, therefore, none is shown or described.

There are two "side" brushes, C², adapted to do the greater part of the work, between 80 which is fixed a foot pedestal, P. Each of these brushes is composed of several sides arranged in polygon form having the bristles on one side of each somewhat longer than those of the other sides. Each of these 85 brushes has a compound motion, viz., a long gradual progressive movement from the toe to the heel of the shoe and return, and a short and rapid reciprocating action in the same plane as the progressive motion. There 90 is one "toe" brush, H³, polygonal in form and adapted to travel from the toe to the instep of the shoe, and over and about the top and sides thereof. This brush also has a compound motion, viz.: a long gradual 95 progressive movement from the toe to the instep and return, and a transverse motion in a direction substantially at right angles to the direction of the progressive motion. There is one heel brush, K¹, adapted to describe a semicircular movement about the heel. This brush has a reciprocating curvilinear motion on a center coinciding with the center of the heel of the shoe.

In action, both the toe brush and the heel 100 brush extend to, cover and overlap, within

their respective zones, the field covered by the side brushes, so that no portion of the shoe is left untouched in the operation. The reciprocating action of the side brushes is produced as follows:—The main drive shaft, A, having bearings in the frame, Z, and the extension arm, Z^1 , respectively, receives the power from a pulley, A¹. Attached thereon by a fin in the keyway, a², is the traveling screw gear, A², forced to revolve with the shaft, A, thereby, but free to slide longitudinally thereon while revolving. Meshed with said gear A², is a screw gear, A³, fixed upon the shaft, B, said shaft lying at right angles to the shaft, A, and arbored in the sliding arms A⁴, and A⁵. The sliding arm A⁴, is adapted to travel along the shaft A, carrying with it the worm gear A², enmeshed with the worm gear A³, and the arm A⁵, is adapted to travel along the stationary guide rod α , which is parallel with the shaft A, and extends from the frame Z, to the extension thereof Z².

Each end of the shaft B, is provided with a balance crank wheel B¹, having a crank pin b, and on each is pivoted a pitman b¹. Supported in standards Z³, on each side of the frame Z, are the guide rods C, upon which the side brush carriers C¹, are mounted, so as to slide freely thereon. The pitmen b¹, are pivoted to these side brush carriers respectively. It is therefore obvious that the revolutions of the shaft B, will convert the rotary motion of the crank wheels B¹, through the pitmen b¹, to a short, rapid reciprocating motion in the side brush carriers C¹, along the guide rods C.

The long gradual progressive motion to the side brushes is produced as follows:—On the drive shaft A, is fixed the bevel gear D, in mesh with another bevel gear D¹, fixed on the vertical shaft d, which has its bearing centrally in the arm z², extending horizontally from the frame Z. On the lower end of the shaft d, is a third bevel gear D², in mesh with a fourth bevel gear D³ affixed to one end of the horizontal shaft d¹. The shaft d¹, has its bearings centrally in the arm z, extending vertically from the frame Z, and carries on its other end a fifth bevel gear D⁴. This bevel gear D⁴, is permanently in mesh with the two oppositely facing bevel gears, E¹ and E², both of which last mentioned gears are idlers on the screw shaft E. Within the inclosure formed by the three bevel gears D⁴, E¹, and E², and centered on the screw shaft E, is the reversing clutch E³. This clutch is centered by means of a fin and a short keyway in the shaft E, so as to cause the shaft E, to revolve with it and yet to be free to slide longitudinally along said shaft between the bevel gears E¹ and E², with each of which it is adapted to engage through the ratchet teeth, e, with which it and said bevel gears

are provided. Clutch E³, is also provided with the annular slot e¹, to permit of the introduction of the pins, e², from the forked end of the horizontal reversing lever F, which lever is pivoted to a lug or post z¹, 70 projecting from the frame Z.

The screw shaft E, is suitably centered in vertical bearings in standards, P and Z⁴, from the frame Z, and is provided for the required distance with a screw thread g, 75 adapted to actuate the nut or traveling piece G, which is centered thereon and tapped with the necessary internal thread to engage therewith. Fixed upon this traveling piece G, and extending upwardly are the aforesaid two arms A⁴ and A⁵, carrying the shaft B. When, therefore, the shaft E, is revolved by the action of the clutch E³, the traveling piece G, progresses slowly and carries along with it the whole construction 85 actuating the side brushes heretofore described.

The eccentric action of the toe brush H³, is produced as follows: On the shaft B, located about centrally, is diagonally fixed the cylindrical compound eccentric cam H, adapted to revolve with said shaft. Incasing this cam is the sleeve H¹, adapted to be actuated by said cam and provided with the bifurcated brush extension rod H², adapted to rest upon the guide bar h, which extends between the uprights, J, J. On the extremity of this rod H², is mounted the toe brush H³. Thus, when the shaft B, is caused to revolve, the cam H, rotating therewith causes the sleeve H¹ to oscillate transversely of the apparatus and also to rock in a vertical plane. The rod H², resting upon the bar h, amplifies this motion at its outer end and causes the toe brush H³, to reciprocate transversely with a dipping motion as it approaches each extreme. At the same time this whole construction actuating the toe brush H³, progresses slowly, being carried along by the traveling piece G, as hereinbefore described. 100

The semi-circular movement of the heel brush K¹, is produced as follows:—On the extreme end of the screw shaft E, is the idler disk I, having the crank pin i, engaging one end of the rod or pitman I¹. The other end of this pitman is freely pivoted to the vertical lever I², which has its fulcrum at its lower terminal in a lug z⁵, and extending upward from the bed plate of the frame Z. To this vertical lever I², at a point above the pivot of the pitman I¹, is freely pivoted the horizontal rod or link I³, which connects said lever I², with one end of the sector gear lever, I⁴. Said sector lever is pivoted centrally to a standard G¹, from the standard P, on the bed plate of the frame Z, and has at its opposite end the teeth meshing with the teeth of the pinion I⁵, which is freely centered in the foot rest 115 120 125 130

P, at a point approximately beneath the center of the heel plate of said rest. Affixed to this pinion I⁵, is the heel brush carrier K.

Centered by a fin and keyway on the screw shaft E, immediately adjacent to the disk I, is the sliding clutch L, adapted to revolve with said shaft and to slide longitudinally thereon, while so revolving and provided with two or more projecting lugs 16 l, adapted to engage in the recesses l¹, in the hub of the disk, I, by the action of the helical expansion spring l². The result of this construction is that the rotary motion of the shaft E, is through the clutch L, imparted to the idler disk I, which, through the pitman I¹, is converted into a reciprocating motion in the lever I². This reciprocating motion is transmitted by the link I³, to the oscillating sector lever I⁴, and thence by the 20 meshing teeth i², to the pinion I⁵, imparting to said pinion and the heel brush carrier K, a reciprocating semi-circular motion.

As it is desirable to have the side brushes C², extend to the extreme heel end of the shoe when operating, it is obvious that the oscillations of the heel brush must be suspended at that stage, hence the disk, I, is made to idle on the shaft E, except when engaged by the slide clutch L, by the pressure of the spring l². This engagement is broken and reestablished by the following construction: In the clutch L, is the annular slot l³, adapted to engage pins in the bifurcated lever L², which is pivoted at its 35 lower end to the bed plate Z, and which is connected intermediately by the link L³, to the lower end of the lever L⁴. This lever L⁴, is pivoted centrally to an upright from the bed plate Z, and has its upper end provided with a roller l⁴, located in the path of the beveled toe g¹, projecting horizontally from the traveling piece G, so as to be forwardly depressed around its fulcrum when said toe makes contact with said roller 45 l⁴, and to be so retained until said contact is removed. By this action the lower end of the lever L⁴, is drawn backward from the heel construction, pulling with it the link L³, and the bifurcated clutch rod L², 50 with its clutch L, and thereby disengaging the contact thereof with the disk I, and thus, but cutting connection with the power in the shaft E, interrupting the action of the heel brush actuating mechanism.

The progressive motion of the side and toe brushes is reversed by means of the clutch E², operated by the shifting lever F, with which it engages as already described. As the sliding side brush carrier C¹, approaches the heel extremity, the projection c, thereon comes into contact with the adjustable collar c¹, on the horizontal shift rod c². This rod is adapted to slide longitudinally in guides in the standards Z³, and is 65 loosely pivoted to the lever F, so that such

contact will shift same on its central fulcrum and thus uncouple the clutch E², from the bevel gear E¹, and couple it up with the opposite bevel gear E³, whereby the direction of revolution of the screw shaft E, 70 is reversed and the carrier G, returns toward the toe end of the machine. When the side brush carrier C¹, approaches the toe end of the brush, the projection c³, comes into contact with the collar c⁴, with a similar result to the one just described, but in the opposite direction, whereby the clutch E², is re-shifted and the shaft E, reversed, and another trip of the traveling piece G, 75 is started.

The side brushes C², having several separate brush sections arranged as a regular polygon, which sections are to be presented in succession to the shoe at successive trips of the traveling piece G, it is necessary to 80 automatically shift these brush sections about the time of the end of one trip and the beginning of another. This is done by having the side brush C², pivoted freely within the bifurcated carrying frame C⁴, 85 and a circular rack M, with radial teeth mounted thereon and concentric therewith, and adapted to engage the spring pawl M¹, when pressure is exerted on the periphery of the polygon C², in a direction contrary to that indicated by the curved arrows, and thus to prevent a rotation of the side brush member C², in such direction, but still leaving the member C², free to revolve in the direction indicated by the arrows. It is necessary, however, to control and restrict such direct rotation, so that the side brush faces shall be held rigid while acting on the shoe, but be free to move sufficiently to present a new brush section when desired. This is 95 provided for by having radial lugs M², standing from the top of the member C², the number thereof corresponding with the number of side brushes, and spaced regularly adjacent thereto.

Pivoted at m, to the brush frame C⁴ is a spring latch. This latch is composed of three parts: the pivoted member M³, latch proper m² and the helical spring m³. The latching member, m², is slidably mounted on 110 the pivoted member, M³, and is provided with a shoulder to engage the helical spring m³ so as to be thereby urged toward the foot rest P. A flat pressure spring, m⁴, pressing upwardly from beneath on the outer part of lever, M³, holds the toe end of the member, m², normally, in position to block the passage of the radial lugs or ridges, M². The effect of this arrangement is that a proper depression of the lever, M³, over the 115 point of contact of the flat spring, m⁴, raises the toe of the latch, m², above a ridge, M², with which it is engaged, whereupon the helical spring, m³, shoots the latch, m², so as to cause the toe end thereof to pass over and 120 125 130

beyond the ridge just released and to be in position, when lowered, to engage the succeeding ridge or radial lug. This raising and lowering is accomplished as follows: 5 Suitably disposed, as on arms, Z^1 , Z^2 , is a trip, M^4 , beveled on its under side as shown in Fig. 1, so as to engage and wedge down the outer end of member, M^3 , when the latter is brought beneath it by the reciprocation of the frame C^4 . This contact is 10 made at the last swift reciprocal stroke of the frame, C^4 , under the action of the pitman, b^1 . The screw shaft, E , carries the traveling piece, G , to a point where the next 15 pull of the pitman will bring about this collision of parts M^3 and M^4 , resulting in the rocking of the former on its pivot, m , and in a hurdling of the ridge, M^2 , by the toe of member, m^2 , as described above. While this 20 is occurring, the reversing gears change the direction of rotation of the shaft, E , and consequently the direction of the traveling piece, G , whereby the frame, C^4 , and member, M^3 , are withdrawn beyond possibility of a second contact by M^2 with trip M^4 . As soon as the former is pulled from beneath the latter, the flat spring, m^4 , restores the toe of latch, m^2 , into its normal position with relation to the ridges, M^2 , leaving 25 30 the brush, C^2 , free to rotate in a proper direction to present the next brush face to the shoe, and until impeded by the following ridge, M^2 , meeting the latch toe, m^2 . This rotation is almost invariably accomplished 35 by the inertia of the mass of the polygonal brush, C^2 , under the action of the momentum of its rapid reciprocal stroke. As soon as the brush face of C^2 contacts with the shoe, this setting of the parts, if not 40 entirely accomplished by momentum, is completed by this contact so that the face in operation on the shoe is held in proper position by the combined effects of the pawl, M^1 , on the rack, M , and the member m^2 on 45 the lug or ridge, M^2 , so as to be locked thereby. The helical spring, m^3 , is also compressed for the next operation. It is obvious that this releasing operation of the check on the rotation of brush, C^2 , must be 50 made at the last reciprocation and must occur but once. Two or more such operations might result in a turning about of two or more brush sides, as the throw caused by the rapid reciprocations has a tendency to rotate 55 the member, C^2 , on its axis, without the aid of any contact with a shoe. And, as the machine to be commercially valuable, must be adapted to operate on shoes of all customary sizes, from a small child's foot to that 60 of a very large man, the trip, M^4 , must be located at the extreme limit of the travel of the carrier, G , and this limit must be located sufficiently distant from the foot rest to accommodate the longest shoe.

65 The object in making the side brushes

consist of several component faces is to furnish one or more brushes to clean the shoe, then a "dip" or blacking supply brush to apply the medium after which a series of brushes to dry and bring up the polish. In 70 my drawings I have shown six faces arranged as a regular hexagon, but it is obvious that any practical number of faces may be employed, as the character of the work might require, as for instance, a machine intended to operate on "russet" shoes 75 might be found after experience, to act most expeditiously with more or less faces.

The "dip" brush face is composed of longer bristles than those used in the cleaning, drying and polishing, so that the extremities of this face shall describe a larger circle in its intermittent rotation, than the circle described by the other brushes. The reason for this is that it is necessary for 85 this face to make contact with the blacking supply, which must, of necessity, be beyond the reach of the other faces, and it is further desirable that this brush should be brought in firmer contact and exert a 90 greater pressure on the shoe, than the cleaning and polishing faces, to insure an efficient application of the blacking to the shoe.

The blacking supply receptacles are two in number, one for each side brush C^2 , and 95 are located at nearly the end of the long progressive trip of these brushes, at the heel end of the machine. They are mounted upon suitable projections from the bed plate Z , at a correct angle to present a flat vertical plane surface of shoe blacking composition in a plane parallel to that of the face of the "dip" brush. Each receptacle is composed of a reservoir N , for water or other reducing liquid, and, directly underneath, a 100 box N^1 , for the blacking. The reservoir has a small outlet provided with a valve n , the stem n^1 , of which protrudes into the line of travel of the lug n^2 , on the box N^1 . This box, N^1 , which is provided with a wire gauze 110 front wall n^3 , to be presented to the bristles of the dip brush, (Fig. 7^a) is not fixed to any portion of the structure, but is merely yieldably fitted about or suspended upon a T shaped plunger N^3 , (provided with the hollow stock, N^2), which fits snugly within it and forms its back wall. The blacking material fills the space between this plunger and the gauze front. The stem of the plunger N^2 , is hollow and is fitted over the red 115 N^4 , projecting from the support or standard, from which it is forwardly urged by the pressure of an expansion helical spring n^4 , but held in limit by the pin n^5 , through opposite slots in the plunger stem. The plunger, N^3 , is also yieldable and the force of the helical spring, n^4 , is transmitted to the box, N^1 . Thus the entire blocking receptacle 120 may be reciprocated horizontally along the support rod N^4 , when the gauze wall n^3 , 125

130

exuding moist blacking, is jolted by the rapid reciprocating strokes of the "dip" brush, the force of the impact being directly through the mass of blacking material and tending to force the material through the gauze. When this brush, carried along by its connections with the traveling piece G, reaches the blacking supply, it jolts, by the action of the pitman b^1 , the wall n^3 , and agitates the entire construction of the blacking container, viz: the gauze front, n^3 , the box, N^1 , to which the gauze is attached, the mass of blacking material within, and the plunger, N^3 , all being guided by the plunger 10 supporter, N^4 , against the helical spring, n^4 , on which supporter the hollow stock, N^2 , is mounted, whereby the lug n^2 , opens the valve n , and permits the liquid to reach the blacking surface; a rapid repetition of these jolts 15 causes a supply of ready moistened blacking to adhere to the brush. The number of these jolts may be regulated, by lengthening or shortening the amplitude of the motion of the plunger N^3 , on the rod N^4 , and by arranging 20 the location of the receptacle nearer or farther from the extreme end of the slow progressive trip. If desired, the air space within the reservoir N, may be compressed so as to force out the liquid in jets, when the 25 valve n , is opened. The two side brushes furnish the entire supply of blacking to the shoe, the toe and heel brushes, spreading it on top and behind, by reason of the overlapping of their respective fields, on the side 30 brush zones, as hereinbefore mentioned.

The successive sides of the toe brush H^3 , are also presented to the shoe at periods corresponding with the changes of the side brush faces. This brush is freely centered, 40 horizontally, within the bifurcated end of the rod H^2 , and has fastened concentrically on one end a radial rack h^1 , Fig. 13, engaging a pawl h^2 , mounted on said rod H^2 , which acts to prevent adverse action, as in 45 the case of the side brush construction as already described. On the opposite end of the brush-stock, H^3 , are arranged radial lugs or ridges, h^3 , (corresponding to lugs, M^2 , in the side brush construction) acted 50 upon by the slideable spring-latch, h^4 , (corresponding to latch m^2 in the side brush construction), which is carried by the spring lever, J^2 , (corresponding to lever M^3 in the side brush construction), which in turn is 55 pivoted at T to an arm of the bifurcated brush holder, H^2 , and which extends rearward so as to be brought under and against the fixed trip, h^5 , (corresponding to M^4 , in function, of the side brush construction) 60 which extends from the bed plate. This trip is adjusted to so interfere with the movement of the lever, J^2 , imparted by its connection with the rod or holder, H^2 , to which it is pivoted, as to swerve it on its 65 pivot, T, so that the tip of the latch, h^4 , at

the opposite end will clear the lug, h^3 , with which it has just been engaged and be free to spring outwardly under the action of the helical spring, H^5 , and to pass beyond said lug, so as to be ready when returned to normal position to impede progress of the succeeding lug. When, by the combined results of the rotation of the cam, H, and the return movement of the carrier G, the lever, J^2 , is freed from contact with trip, h^5 , the pressure spring, J^3 , causes it to return to its normal position so that the tip of latch, h^4 , will return to a place in the line of rotation of the next lug or ridge, h^3 . As in the case of the side brushes, this action takes place 75 but once, that is, at the last rapid reciprocation transversely and while the reversing gears are changing the direction of the movement of the carriage, G. As momentum does not aid in turning the toe brush, as is 80 the case in the side brush action, this toe brush does not attain its proper position until contacting with the toe of the shoe. When, however, this contact occurs, this brush immediately assumes its proper angle 85 with the shoe, by rotation on its axis, and is then held locked between the latch h^4 , pressing the ridge h^3 , and the pawl, h^2 , pressing the rack, h^1 , on the opposite end of the brush stock, H^3 . 90

The timing of the machine is such that the traveling-piece G shall start at the toe end of the machine and shall make as many complete journeys to the heel end and return, as there are faces on the side (and toe) 100 brush polygons, viz: in the hexagonal form, six complete trips, so as to give each respective side a complete period of activity on the shoe during an entire round trip. It is, of course, essential to stop the machine 105 after the final trip, at which time the side and toe brushes must be in the same position as they were when the operation began, and thus ready for another complete operation. This is accomplished by mounting a 110 cam, O, on a suitable bearing from the frame, Z, the periphery of which cam is in the contour of one complete turn of a regular spiral, whereby the inequality of radii, o, is produced. Concentric with this cam and adapted to move with it and carry it along is the ratchet wheel, O^1 , having as many teeth as the side brushes have faces. Suitably attached to the traveling piece G is the spring pawl O^2 , adapted to engage, one 115 at a time, the teeth on said ratchet wheel, at the termination of each trip to the toe end, and to carry said ratchet and cam about on their common axis a distance equal to the length of one tooth. A check pawl, O^3 , is 120 interposed to prevent reverse action of the ratchet. Resting on the periphery of the cam O is a roller centered in the end of the vertical rod, C^4 , which rod bears downwardly through guide channels in the pieces, 125 130

σ^1, σ^2 , projecting from the frame, Z. At the beginning of the operation, the roller end of the rod rests within the indentation σ . It is therefore evident that, as the ratchet O^1 5 is intermittently rotated by the pawl O^2 , the rod, O^4 will be evenly raised a proportionate part of the distance, σ , represented by the difference between the two radii of the spiral cam, O, and the completion of the 10 final (sixth, in this construction) trip of the traveling piece G, will carry the outer terminal of the spiral under and beyond the roller rod O^4 , so that the roller will ride over the edge thereof and drop into the indentation, σ . At the upper end of the rod 15 O^4 is attached any of the conventional electric contact breakers, so that the drop of the said rod will open the circuit and stop the machine.

20 As I do not include any special form of coin controlled mechanism for connecting the motive power, I do not describe such construction.

The foot rest is placed directly forward 25 of the heel brush construction, and in the path of the toe brush and between the line of travel of the two side brushes. A yielding and self-adjusting pressure to the shoe is imparted to each side brush by means of the 30 pressure-spring C^5 , one end of which is fastened to the side brush carrier C^1 , and the other end presses against the bifurcated frame C^4 , whereby the brush, C^2 , is urged toward the shoe. Freedom from lateral 35 motion in this respect is provided for by having the bifurcated frame C^4 , adaptably adjusted to slide within the channeled guide piece, C^3 , on the carrier, C^1 .

A spring bar, H^4 , mounted on uprights, J, 40 and acted upon by the helical springs, J^1 , supplies the pressure necessary to keep the toe brush in proper contact with the front part of the shoe. If desired, the last brush face of the side and toe brushes may be provided with a cushion, or other fabric such as 45 canvas or tough muslin, which may be substituted for bristles to complete the polish.

By reason of the rapid reciprocations of the side and toe brushes, combined with the 50 gradual progressive motion back and forth along the shoe, it is desirable, if not absolutely essential, to provide a means for the instant stopping of all motion, should the foot of the user, for any reason, assume an 55 improper position on the pedestal or foot-rest, P. It is true that while the side brushes are yieldably mounted and are urged into contact with the shoe, by the pressure of the springs, C^5 , yet the possibility of an abnormal knock on the foot, if 60 not correctly placed on the pedestal, by these brushes in their rapid vibrations, is not entirely absent. It is therefore an integral part of my invention to provide an automatic check to all action of the brushes, 65

whenever the foot is not properly stationed on the pedestal P. I accomplish this result by a peculiar and novel construction of my pedestal or foot rest, in which I employ means adapted to shut-off all motive power whenever the foot is not correctly placed. 70

The spring-top, P^1 , on foot-rest, P, the rods, P^2 , and the contact breakers, P^3 , shown in Figs. 1, 2, 3, 11 and 12, show parts of a safety foot-rest described and claimed in my 75 divisional application No. 866,410, filed October 12, 1914.

Having thus explained the nature of my invention and described and shown a way of constructing and using the same, although 80 without attempting to set forth all of the forms in which it may be made or all of the modes of its use, what I claim is—

1. In a shoe polishing machine, the combination of a carriage, means to reciprocate 85 the carriage, brushes connected with the carriage to reciprocate therewith, means imparting to the brushes a reciprocatory movement independent of that caused by the reciprocations of the carriage though in the 90 same direction and a foot rest adjacent to the brushes.

2. In a shoe polishing machine, the combination of a carriage, means to reciprocate the carriage, brushes connected to the carriage to reciprocate therewith, means imparting to the brushes a reciprocatory movement independent of that caused by the reciprocations of the carriage though in the 95 same direction a blacking apparatus disposed so as to be intermittently touched by the brushes while reciprocating.

3. In a shoe polishing machine, the combination of a carriage, means to reciprocate the carriage, guides, brushes transversely 100 yieldably mounted thereon and connected to said carriage to reciprocate therewith, means imparting to said brushes a reciprocatory movement independent of that caused by the reciprocations of the carriage though in the 105 same direction, and a foot rest adjacent to said brushes.

4. In a shoe polishing machine, the combination with a foot-rest, of a polygonal brush revolvably mounted adjacent the foot-rest, 110 means to cause the brush to travel back and forth along the foot-rest, means to reciprocate the brush during its travel, and means operative upon the arrival of the brush at one point in its travel to rotate the brush to present another face of the brush to the foot-rest, and means to stop the brush after a desired period of movement.

5. In a shoe polishing machine, the combination of a blacking container, a polygonal 115 brush axially mounted, means to rapidly reciprocate the brush, and means to slowly carry the brush while reciprocating so as to bring a given side thereof into jolting contact with the blacking container. 120

6. In a shoe polishing machine, the combination of a blacking container having a flat yieldable dispensing face and polygonal brush having an extended face and rotatably mounted, means to reciprocate said brush, means for turning said extended face into a plane parallel with the dispensing face of said container, and means for bringing said extended face, while reciprocating, into direct collision with said dispensing face. 70
7. In a shoe polishing machine, the combination of a foot-rest, a blacking container having a flat yieldable dispensing face, a polygonal brush having an extended face to receive and apply blacking material, means to reciprocate said brush, means to bring the extended face of said brush, while reciprocating, into direct collision with said dispensing face, and means to carry said extended face, after such collision and while reciprocating, into a line substantially parallel with said foot-rest. 75
8. In a shoe polishing machine, the combination with a foot-rest, of a guide adjacent thereto, a polygonal brush revolvably and yieldably mounted thereon and adapted to slide longitudinally thereon, means to cause said brush to travel back and forth along said foot-rest, means to reciprocate said brush while so traveling, means to cause said brush to rotate a distance of one face at the completion of each back and forth trip, and means to stop all motions of said brush upon the completion of as many trips as said brush has sides, so as to return said brush to its original axial position when stopped. 80
9. In a shoe polishing machine, the combination of a yieldable pervious blacking receptacle, a movable brush, means to rapidly reciprocate the brush, and means to carry the brush, while reciprocating, into contact with the blacking receptacle so as to receive blacking therefrom. 85
10. In a shoe polishing machine, the combination of a yieldable pervious blacking receptacle, a tank for containing a solvent for the blacking material in the receptacle, a channel to carry said solvent to said blacking material, a brush, means to reciprocate the brush, means to carry said brush while reciprocating into jolting contact with said blacking receptacle, and means whereby the jolting of the yieldable receptacle will cause a flow of the solvent through the channel. 90
11. In a shoe polishing machine, the combination of a yieldable pervious blacking receptacle, a tank containing a solvent, a channel between said receptacle and said tank, a valve in said channel, means to operate said valve by the yielding of said receptacle, a brush, means to cause said brush to impart a yielding motion to said receptacle. 95
12. In a shoe polishing machine, the combination of a yieldable pervious blacking receptacle, a tank communicating therewith, a valve between said tank and said receptacle, means to open said valve by the yielding of said receptacle, a brush, means to reciprocate the brush and to carry it into jolting contact with said receptacle. 100
13. In a shoe polishing machine, the combination of a foot-rest, a yieldable pervious blacking container, a tank communicating therewith, a spring-closed valve controlling said communication, a member on the yieldable container to operate the valve, a polygonal brush having an extended face to reach said container, means to reciprocate said brush and means to operate intermittently during the reciprocations of the brush to turn the same to successively present new faces of the brush to the foot-rest, the extended face being adapted at one time in its travel, to operate the valve and collide with the blacking container. 105
14. In a shoe polishing machine, the combination of a foot-rest, a polygonal brush pivotally mounted adjacent thereto, a circular rack on said brush, a check pawl to engage said rack, ridges on said brush corresponding in number to the sides thereof, a spring latch to engage said ridges, a trip to disengage said latch, means to reciprocate said brush, and to carry the latch into contact with the trip and disengage the latch and the ridge and set the brush free to rotate by momentum of its reciprocal motion. 110
15. In a shoe polishing machine, the combination of a foot-rest, a carriage, means to reciprocate said carriage, a brush connected to said carriage, to reciprocate therewith, means to cause said brush to oscillate transversely and also to rock in a vertical plane, while reciprocating. 115
16. In a shoe polishing machine, the combination of a foot-rest, a reciprocable carriage, a shaft thereon, a cylinder mounted thereon at an angle to its longitudinal axis, a sleeve incasing said cylinder, a brush connected to the sleeve whereby the rotation of the shaft will cause the brush to reciprocate laterally in a curved line and means to reciprocate said carriage and to rotate said shaft. 120
17. In a shoe polishing machine, the combination of a foot-rest, a carriage, means to reciprocate the carriage, a polygonal brush pivotally mounted to reciprocate therewith, a circular rack on said brush, a check pawl to engage the rack, ridges on said brush corresponding in number to the number of sides thereof, a spring latch to engage said ridges, a trip to disengage said latch, means to carry said brush between said foot rest and said trip, so as to bring said latch into engagement with said trip, whereby one of said ridges is disengaged from the latch, and the brush is set free to rotate by subsequent contact with a shoe on said foot rest. 125
18. In a shoe polishing machine, the com- 130

bination of a foot-rest, a rotatably mounted polygonal brush, checking means to normally prevent rotation of the brush, means to cause the brush to travel back and forth past the foot-rest, means to reciprocate the brush during its travel, means operative at a certain point in the travel of the brush to release the checking means whereby further movement of the brush will advance another face of the brush toward the foot-rest, and means to stop movement of the brush after one complete revolution thereof.

19. In a shoe polishing machine, the combination with a reciprocating carriage, of a foot-rest, polygonal brushes rotatably mounted and connected to said carriage so as to be moved back and forth therewith, checking means to normally prevent rotation of the brushes, means operative by the reciprocation of the carriage at a certain point in the travel of the brushes to release the checking means whereby the further movement of the brushes will advance another brush face toward the foot-rest, a projection on said carriage, a ratchet wheel having as many teeth as each brush has sides and suitably positioned to be rotated the distance of one tooth with each reciprocation of the carriage by the engagement of said wheel with said projection, so that such reciprocation of the carriage will effect the simultaneous rotation of said brushes and said ratchet wheel and means actuated by said ratchet wheel to stop the reciprocations of said carriage at the completion of one rotation of said wheel.

20. In a shoe polishing machine, the combination of a foot-rest, a carriage, means to reciprocate said carriage, a shaft thereon, means to rotate the shaft, a crank disk on the shaft, a guide adjacent to the foot rest, a brush yieldably mounted on the guide, a pitman pivoted at one end to said brush mounting and at the other end to said crank disk.

21. In a shoe polishing machine, the combination of a foot-rest, a screw shaft, a carriage reciprocated longitudinally along said foot-rest by the rotation of said shaft, brushes on opposite sides of said foot-rest and connected to said carriage to reciprocate therewith, means imparting to said brushes a reciprocatory movement independent of that caused by the reciprocation of the carriage, though in the same direction, a lever pivoted beneath the foot-rest, a brush attached to the lever, a clutch splined on the screw shaft, and idler on the screw shaft adapted to be engaged by said clutch and operated thereby, means to oscillate the lever by the rotation of the idler, means to engage and disengage the clutch and idler by the motion of the carriage so as to suspend the revolutions of the idler at the approach of

said side brushes, and means to rotate said screw shaft, substantially as described.

22. In a shoe polishing machine, a carriage, means to reciprocate the carriage longitudinally, a transverse shaft on the carriage, a worm gear on said shaft, a drive shaft, a worm gear splined thereon and in mesh with the former worm gear, a plurality of reciprocating brushes connected to said carriage so as to reciprocate therewith, actuating connections between said transverse shaft and said brushes, whereby the brushes are caused to rapidly reciprocate independently of the reciprocations caused by the motion of the carriage.

23. In a shoe polishing machine, a carriage, means to reciprocate the carriage, a foot-rest, brushes disposed on opposite sides of the foot-rest and connected to said carriage to reciprocate therewith, means imparting to the brushes a reciprocatory movement independent of that caused by the reciprocations of the carriage, though in the same direction, a brush disposed substantially between the aforesaid side brushes and connected to said carriage to reciprocate therewith, means imparting to the last mentioned brush a reciprocatory motion independent of and at substantially right angles to that caused by the reciprocations of the carriage.

24. In a shoe polishing machine, the combination of a foot-rest, an oscillating brush at one end thereof, longitudinally traveling brushes at opposite sides thereof, means to suspend the oscillations of said end brush while the traveling brushes are operating within the arc of said oscillations, and means to actuate said end and said side brushes, substantially as described.

25. In a shoe polishing machine, a foot-rest, a brush adapted to be slowly carried along the side of a shoe resting thereon, means to so slowly carry said brush, and means to rapidly reciprocate the brush while being so carried.

26. In a shoe polishing machine, a foot-rest, a brush adapted to be slowly carried over the toe, front and top of a shoe resting thereon, means to slowly carry the brush as described and means to rapidly oscillate transversely and also to rock said brush in a vertical plane.

27. In a shoe polishing machine, a foot-rest, a plurality of brushes adapted to be slowly carried along the sides of a shoe placed upon said foot-rest, means to slowly carry said brushes as described, means to cause said brushes to rapidly reciprocate while being slowly carried as described, another brush adapted to be slowly carried over the toe, front and top of a shoe resting on said foot-rest, means to slowly carry the last described brush as stated, and

means to cause said brush to rapidly oscillate transversely and to rock in a vertical plane while so slowly being carried.

28. In a shoe polishing machine a polygonal brush adapted to be slowly carried back and forth along the sides of a shoe resting on a foot-rest adjacent thereto, means to cause a different side of this polygonal brush to be presented to said shoe at each trip, a blacking apparatus, means to present one side of the polygonal brush thereto during one of its trips so as to receive a supply of blacking therefrom, means to thereafter present the side so supplied with blacking to the shoe on said foot-rest, and means to rapidly reciprocate the brush during its carriage back and forth.
29. In a shoe polishing machine, a polyg-

onal brush adapted to be slowly carried back and forth over the top of the toe portion of a shoe resting on a foot-rest adjacent thereto, means to cause a different side of said polygonal brush to be presented to the shoe at each trip and means to rapidly reciprocate said brush in a direction substantially at right angles to the direction of the slow back and forth motion, during the continuation of said slow motion.

In testimony whereof I have signed my name to this specification, in the presence of two subscribing witnesses, this fourth day of December, A. D. 1911.

JAMES ELBERT BIRDSALL.
